N-HALOPHENYL DERIVATIVES OF LEUCAURAMINE

Clyde S. Adams, Yellow Springs, Marjorie J. Cormack, Dayton, and Mary Lou Frazier, Springfield, Ohio, assignors to The National Cash Register Company, Dayton, Ohio, a corporation of Maryland

**No Drawing. Application November 1, 1955
Serial No. 544,376**

6 Claims. (Cl. 260—570)

This invention relates to the N-halophenyl derivatives 15 of leucauramine having the general structure

where R is taken from the group consisting of o-chloro; o-bromo; m-chloro; m-bromo; p-chloro; p-bromo; 2,3-dichloro; 2,3-dibromo; 2,4-dichloro; 2,4-dibromo; 2,5-dichloro; 2,5-dibromo; 3,4-dichloro; 3,4-dibromo; 3,5-dichloro; 3,5-dibromo; 2,3,4-trichloro; 2,3,4-tribromo; 3,4,5-trichloro; 3,4,5-tribromo; 2,3,5-trichloro; 2,3,5-tribromo; 2,4,5-trichloro; 2,4,5-tribromo; 2,3,4,5-tetrachloro; and 2,3,4,5-tetrabromo.

These are solid crystalline materials, relatively colorless, which may be used as color-reactants because they turn to a dark blue or green-blue color on coming into adsorption-contact with acidic types of inorganic compounds such as, for instance, attapulgite, halloysite, kaolin, bentonite, aluminum-sulfate, zeolite material, silica gels, magnesium trisilicate, and zinc-sulfide, among others, and are useful in solution for printing in color on paper coated or filled with such adsorbents. Otherwise, they are very light-stable and atmospherically-stable both in their leucauramine forms and in their colored states.

The great utility of these compounds, as at present known, is their use in transfer coatings in manifold record systems wherein the rear surface of an overlying sheet of record material is coated with a composition containing one or more of the novel leucauramine derivatives and the underlying sheet containing particles of the acidic reactant. In such manifold systems the leucauramine derivative is usually dissolved in a suitable solvent and carried as droplets in a hydrophilic colloid film coating on the rear of the overlying sheet. When the two sheets are in contact and a printed or written impression is made on the top surface of the overlying sheet, rupturing the film at the points of pressure, the liquid solution is released locally so it may be adsorbed by the acidic particles in the coating of the under sheet. Such contact will make blue or blue-green marks on the top surface of the under sheet at the points of pressure. Such a manifold system is disclosed in U. S. Patent 2,712,507 which issued July 5, 1955, on the application of Barrett K. Green.

The halogenated derivatives of N-phenyl leucauramine are much more suitable for the manifold systems mentioned than the known unihalogenated N-phenyl leucauramine, because they are less volatile, they have increased solubility in oil, and they are much more stable com-

pounds in the leuco form when subjected to atmospheric conditions and light.

The leucauramine derivatives also are useful in solid powdered form as one of two solid powdered materials dispersed in a coating on one side of a record material sheet, the second material being one of the acidic inorganic materials which cause a blue or blue-green color to appear when marked with a stylus. Such a record sheet is disclosed in U. S. Patent 2,505,470 which issued, on the application of Barrett K. Green, on April 25, 1950.

10 on the application of Barrett K. Green, on April 25, 1950.

15 One process of making the novel compounds consists of the steps of condensing molar equivalents of Michler's hydrol and a selected halogenated aniline in hot ethyl alcohol; concentrating the reaction mixture as far as necessary to cause precipitation on cooling; filtering; purifying the crude material by treating a benzene solution of it with fuller's earth and activated charcoal; and then precipitating out the reaction product by the addition of petroleum ether. The general equation for this reaction is
20 as follows:

20. as follows:

where X is a halo-substituted aryl nucleus.

Leucauramine itself has the structure:

50 The novel derivatives of this invention may be considered as derivatives of leucauramine in that one of the hydrogen atoms attached to the (1)N has been replaced by a halo-substituted phenyl group.

As a first specific example of the process, consider the
55 making of N-(*o*-chlorophenyl)leucauramine:

25.6 grams (0.2 mole) of o-chloraniline, and

54.0 grams (0.2 mole) of Michler's hydrol are dissolved in 200.0 grams of ethyl alcohol

60 in a round-bottomed flask, fitted with a water-cooled reflux condenser. The solution is refluxed for four hours on a steam bath after which the solution is allowed to cool to room temperature. The crystals which have separated out are filtered off by suction and washed with 65 small amounts of cold ethyl alcohol. The filtrate may be concentrated for additional crops of crystals. The resultant crude product is dissolved in 1½ liters of hot benzene, treated with activated charcoal, and fuller's earth, and filtered. The filtrate is evaporated to approximately 70 200 milliliters, cooled, and the reaction product precipitated out with petroleum ether. The resulting pure ma-

terial is a white crystalline substance. Following is a representation of the reaction:

The m-chlorophenyl and p-chlorophenyl derivatives may be made by using in place of the o-chloroaniline used in the example, m-chloroaniline or the p-chloroaniline.

The o-bromophenyl, m-bromophenyl, and p-bromophenyl derivatives may be made by using, instead of the chlorinated anilines, the selected brominated anilines, using the same relative molecular proportions.

The dichlorophenyl, trichlorophenyl, tetrachlorophenyl, dibromophenyl, tribromophenyl, and tetrabromophenyl derivatives may be made in the same manner by using the selected halogenated aniline in the same molecular proportions.

As a second specific example, the N-(2,4-dichlorophenyl)leucauramine, is prepared by taking:

32.4 grams (0.2 mole) of 2,4-dichloroaniline, and 54.0 grams (0.2 mole) of Michler's hydrol and dissolving in 200.0 grams of ethyl alcohol.

The rest of the procedure is identical to that given in the first specific example, according to the following equation:

and results in a white crystalline compound. The other dichloro and dibromo derivatives may be prepared according to the same procedure.

In a similar manner the trichlorophenyl, tribromophenyl, tetrachlorophenyl and tetrabromophenyl derivatives may be made simply by choosing the selected halogenated aniline for the reaction using the same molecular proportions.

Mixed types of N-chloro-bromophenyl derivatives may be made in exactly the same way by using anilines in which both bromine and chlorine are substituted in the same phenyl group.

5 What is claimed is:

1. The N-halophenyl derivatives of leucauramine, which derivatives have the general structure:

20 where R is taken from the group consisting of o-halo; m-halo; p-halo; 2,3-dihalo; 2,4-dihalo; 2,5-dihalo; 3,4-dihalo; 3,5-dihalo; 2,3,4-trihalo; 2,3,5-trihalo; 3,4,5-trihalo; 2,4,5-trihalo; and 2,3,4,5-tetrahalo, and in which the halo substituent in any position may be taken from the group consisting of chlorine and bromine.

25 2. The N-halophenyl derivatives of leucauramine, which derivatives have the general structure:

40 where R is taken from the group consisting of o-chloro; o-bromo; m-chloro; m-bromo; p-chloro; p-bromo; 2,3-dichloro; 2,3-dibromo; 2,4-dichloro; 2,4-dibromo; 2,5-dichloro; 2,5-dibromo; 3,4-dichloro; 3,4-dibromo; 3,5-dichloro; 3,5-dibromo; 2,3,4-trichloro; 2,3,4-tribromo; 2,3,5-trichloro; 2,3,5-tribromo; 3,4,5-trichloro; 3,4,5-tribromo; 2,4,5-trichloro; 2,4,5-tribromo; 2,3,4,5-tetrachloro; and 2,3,4,5-tetrabromo.

45 3. The compound N-(2,5-dichlorophenyl)leucauramine, having the structure:

55 4. The compound N-(m-bromophenyl)leucauramine, having the structure:

5

5. The compound N-(m-chlorophenyl)leucauramine, having the structure:

5

6

6. The compound N-(2,4-dichlorophenyl)leucauramine, having the structure;

15
